(57) **CLAIM**

The ornamental design for a female film dispenser half for use cordless film roll, as shown and described.

DESCRIPTION

FIG. 1 is a perspective view of a female film dispenser half for use cordless film roll;

FIG. 2 is a front view thereof;

FIG. 3 is a top view thereof;

FIG. 4 is a left side view thereof;

FIG. 5 is a rear view thereof;

FIG. 6 is a bottom view thereof; and,

FIG. 7 is a cross-sectional view taken in the plane of line 13-13 of FIG. 4.

The right side view forms no part of the claimed design of the female film dispenser half of FIGS. 1-7.

The longitudinal cross-sectional view of FIG. 7 is included to illustrate the contour of the external surface of the female film dispenser half, in particular, to illustrate the cross-sectional shape of continuous external helical recesses defined in the external surface of the female film dispenser half.

The dot dash lines shown in the figures that are immediately adjacent to the shaded areas and define unshaded regions represent the bounds of the claim, while all other broken lines illustrate the portions of the design that form no part of the claimed design. None of the broken lines form any part of the claimed design.
